ABSTRACT OF THE DISCLOSURE

A cathode ray color display having a single gun with a phosphor responsive to a condition of the electron beam to vary the color of light output. The condition is established by an auxiliary field having a boundary adjacent the deflection zone, between the zone and the phosphor screen, and generally at right angles to the path of the electron beam throughout a scan pattern.

This application is a continuation-in-part of my application entitled "Beam Deflection Device," Ser. No. 697,240, filed Nov. 18, 1957, now Patent 3,205,391, dated Sept. 7, 1965.

This invention relates to a cathode ray color display system and more particularly to a display system with a color control dependent on a condition of the electron beam.

The cathode ray tube color display devices in wide use today incorporate three electron guns and have a screen made up of dots of red, blue and green phosphors together with an apertured plate or shadow mask located immediately adjacent the screen, which has a masking effect that insures that a beam from the appropriate gun strikes the correct color dots. The three beam tube is difficult and expensive to manufacture as it requires very precise physical alignment of the gun structures, the apertured plate and phosphor screen. Other color display systems have been tried, including a rotating color wheel, for example, but have not been satisfactory commercially.

A principal object of this invention is the provision of a single gun color display tube utilizing a condition of the electron beam to vary the color of the light output of the device.

In accordance with one embodiment of the invention, a phosphor is used in the screen which is responsive to an energy characteristic of the beam to emit different colors. More specifically, the color of the light may vary with the velocity of the electron beam, or with the frequency thereof.

In accordance with another embodiment of the invention, a single gun tube utilizing the shadow mask has a beam source which establishes a slight diffraction of the beam to correspond with the various color dots. This simulates the three separate sources which are presently used, but is substantially simpler and more economical to manufacture.

One feature of the invention is the provision in the color display system of a cathode ray tube having a single electron emitting and beam forming gun means and having a screen with multicolor light output dependent on a condition of the electron beam, means between the gun and the screen for deflecting the beam to scan the screen, means between the deflecting means and the screen for establishing a beam modifying field which is generally uniform with respect to the field of the beam deflection means, and a source of beam modifying potential responsive to the color to be displayed, connected with the field establishing means for imparting to the beam a con-

dition modulation to vary the color of light output of the screen, independently of the scanning of the beam.

Another feature is that the color of the light output of the screen is a function of the velocity of the beam striking the screen and a grid is located immediately adjacent the deflecting means having a velocity modifying potential applied between the grid and the screen.

A further feature is that the deflecting means has an apparent center of deflection and the grid is concentric with the deflection center, a control voltage on the grid effecting a linear velocity modulation of the beam without distorting the deflection field. More specifically, the beam modifying field has a nonlinearity which is less than an elemental area of the screen throughout the entire surface thereof.

In accordance with one specific embodiment of the invention, the energy of the beam is modulated by varying the beam velocity and the screen is made up of multiple layers of phosphor of different colors so that electrons having different velocity penetrate to different layers and excite different colors of the phosphor. In accordance with another embodiment of the invention, the screen has a phosphor which gives off different colors in accordance with the frequency of velocity variations of the beam.

Further features and advantages of the invention will readily be apparent from the following specification and from the drawings, in which:

FIGURE 1 is a diagrammatic view of an apparatus embodying the invention;

FIGURE 2 is a block diagram of a color display system embodying the invention;

FIGURE 3 is a diagrammatic illustration of a display tube embodying the invention;

FIGURE 4 is an enlarged fragmentary section of a portion of the tube of FIGURE 3;

FIGURE 5 is a diagrammatic view similar to FIGURE 3, illustrating a modified tube;

FIGURE 6 is a diagrammatic view similar to FIGURE 3 illustrating the invention as embodied in a single gun shadow mask tube; and

FIGURE 7 is an enlarged fragmentary view, similar to FIGURE 4, illustrating the tube of FIGURE 6.

In the parent application identified above, various tube constructions are shown in which an auxiliary beam accelerating field is established. More particularly, in accordance with an important feature of the parent application, the amplitude of scan of the tube may be modified by the establishment of an appropriate accelerating field gradient. Where the accelerating field gradient is generally at right angles to the path of the deflected beam, a linear velocity modulation of the beam is effected which is utilized to effect a color change of the resulting display. Linear modulation means that the variation in the modifying field changes only the velocity of the beam and does not have a significant effect on the deflection. By a significant effect on deflection, it is meant a deflection which would be apparent to an observer and would degrade the quality of the picture. If the size of the spot produced by the electron beam is considered to define an elemental area of the picture displayed, an irregularity which causes a deviation of the beam less than a beam diameter is generally not significant while a deflection of greater amplitude is.

Turning now to FIGURE 1 of the drawings, cathode ray tube 10 has a gun structure 11 which forms an electron beam 12. Beam deflection coils 13 are located about the neck of the tube 10 and are connected with a suitable source of deflection signals, not shown. The beam is deflected about an apparent deflection center 14 to scan the face or screen 15 of the tube. A phosphor coating on the inside of the tube face is excited by the electron beam

and gives off light. The deflection signals connected with coils 13 may, for example, cause the beam to scan the face of the tube with horizontal lines moving from top to bottom of the screen, in a manner used with commercial television.

In the tube of FIGURE 1, the beam is deflected at a low energy level as the grid 16 is operated at a potential much lower than the potential on the screen of the tube. A second grid 18 is interposed between the grid 16 and the screen of the tube. The grids 16 and 18 are parallel and are generally spherical in configuration about the center of the deflection of coils 13. Connected between grids 16 and 18 is a signal source 20 which establishes a control potential for the beam velocity. If the signal from source 20 is rapidly varying, the electrons are bunched as they pass between the grids at a frequency related to the frequency of the exciting signal. If a relatively low frequency or slowly varying DC potential is applied between the grids, the velocity of the electrons varies accordingly.

If desired, the velocity accelerating potential may be applied between the grid 16 and the screen 15 of the tubes, or between the grid 16 and the screen 15, if the grid 18 is eliminated, as illustrated in broken lines. In order to achieve linear velocity modulation over the entire scan region of the deflection system, it is desirable that the accelerating potential be applied between substantially parallel surfaces so that the path of the electron beam is substantially normal to the lines of force of the varying field.

In FIGURE 2, the invention is illustrated as embodied in a color television display system. The television signal is received by an antenna 25 and coupled through radio frequency and intermediate frequency amplifier 26. The picture information is derived from the received signal and amplified at 27, and split into two portions, the luminance or brightness information which passes through channel 28 and the color information in channel 29. The synchronizing signals are derived from the received signal and sweep circuits 30 generate the deflection potentials which are applied to deflection coils 31 around the neck of color display tube 32. A high voltage rectifier 33 derives, from the sweep circuit, a potential which is applied to the screen 34 of the tube. The sound is amplified at 35 and connected with a speaker 36. The display screen of the tube is coated with a phosphor which is responsive to a velocity condition of the electron beam to develop a light output of differing colors. Mounted within the tube, between the deflection coils 31 and screen 34 are a pair of spaced grids 40 and 41, both of which are generally spherical in configuration and have a center coinciding generally with the center of deflection of the tube. The color information from color circuitry 29 is coupled to the grids 40, 41 in the form of varying voltage which establishes a velocity condition suitable to stimulate the phosphor of screen 34 causing it to emit light of appropriate colors corresponding with the received signals. As the two grids 40 and 41 are generally concentric about the center of deflection, the beam modulating field established between them is substantially normal to the deflected beam and a linear modulation characteristic is achieved. Thus, modulation of the beam velocity does not affect the size or linearity of the picture. A luminance or brightness signal is coupled from luminance channel 28 to the cathode of the display tube.

As pointed out in connection with FIGURE 1, the color signal may be connected between one of the grids 40, 41, and the screen 34 of the tube, if desired. Where the modulating signal is connected between grid 40 and the tube screen, the grid 41 is omitted.

Turning now to FIGURES 3 and 4, a specific embodiment of the invention is illustrated. The tube 45 has a screen which includes a glass plate 46 on the inner surface of which are deposited three phosphor coatings 47, 48

and 49, each of which, when excited by the electron beam, gives off a different color. The phosphor layers 48 and 49 are transparent so that light emitted by the layers 47 and 48 is visible. The three phosphor layers may, for example, represent the colors red, blue and green. A tube 5 utilizing such phosphors is available from Pan-Aura Corporation, Arlington, Va.

In accordance with the invention, a wire mesh grid 50 is incorporated in the tube between the center of deflection 51 and screen 46. A suitable signal from a color signal source 52 is applied between grid 50 and screen 46 effecting a velocity modulation of the electron beam in accordance with the color information. As seen in FIGURE 4, the relationship of grid 50, the center of deflection 51 and screen 46 with its phosphor coatings is such that equipotential lines 53 and 54 are substantially at right angles to the paths 55 of the electron beams. The signal applied between grid 50 and screen 46 varies the velocity of the electron beam and thus the energy of the electrons at the time they strike the screen. The only effect, however, is on the beam velocity. There is no appreciable interaction of the modulation with beam deflection. The velocity or energy variations of the beam cause the electrons to penetrate to varying depths of the multiple phosphor coating on the inner surface of glass plate 46. The principal portion of the beam energy is given up at the depth at which the electrons stop. Accordingly, the color of the light output varies with the color signal.

A modified form of the invention is illustrated in FIGURE 5. Here, the tube 60 has a screen 61 with a single phosphor layer 62 on the inside thereof. The phosphor 62 includes a mixture of different materials which emit different colored light when excited at different frequencies. The amount of light given off depends on the average beam velocity at the frequency of excitation. In this embodiment of the invention an auxiliary grid 63 is provided which, again, is generally spherical in configuration about the center of deflection 64. The color signal is coupled to an oscillator 65 which has an output that is variable both in frequency and in amplitude, the frequency representing the hue of the color information and the amplitude representing the degree of saturation of the color. The output of oscillator 65 is connected between auxiliary grid 63 and screen 62 and causes a velocity modulation of the electrons at a high frequency, resulting in bunching of the electrons at the oscillator frequency. Again, the modulation is effected linearly so that the beam deflection or scanning are not impaired.

FIGURES 6 and 7 illustrate the incorporation of the invention in a single gun tube utilizing the dot-mask principle. Tube 70 has a single electron gun beam source 71. The screen 72 has on its inner surface a phosphor made up of small areas or dots of materials which give off different colors, as red, blue or green, when struck by the electron beam. Inside the tube and closely adjacent the phosphor coating 73 is a metal plate 74 having therein a series of small holes or apertures 75. Each of the holes is appropriately related to an elemental area of three color dots of the phosphor 73 so that the electron beam passing through the hole strikes one or a combination of the color dots, determining the resulting color seen by the viewer.

In accordance with the invention, a grid 76, in the tube 70 immediately adjacent the deflection zone, has applied thereto from the color circuitry 77 a signal which effects a slight diffraction of the electron beam, resulting in a control of the path of the beam through the mask aperture. This causes the beam to strike an appropriate color dot or combination of color dots to reproduce the desired hue. In this case, the velocity modulation of the beam is not linear but is intentionally made slightly nonlinear so that the beam path is altered in accordance with the color signal. However, the nonlinearity is not great enough to affect the scan. During the receipt of a white

area or of a black and white signal, the beam travels through grid 76 without a change in direction and excites each of the color dots.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In a color display system: a cathode ray tube having a single electron emitting and beam forming gun means and having a screen with a multicolor light output dependent on a condition of the electron beam; means between said gun and said screen to establish a field for deflecting said beam to scan said screen; means, between said deflecting means and said screen, for establishing a beam modifying field with a boundary adjacent the deflecting field which modifying field is generally uniform with respect to said deflecting field; and a source of beam modifying potential, responsive to the color to be displayed, connected with said field establishing means for imparting to said beam a condition modulation to vary the color of light output of said screen, independent of the deflection of the beam.

2. The color display system of claim 1 wherein the color of the screen light output is a function of a velocity condition of the beam striking the screen and in which a grid is located immediately adjacent said deflecting means and a velocity modifying potential is applied between said grid and said screen.

3. The display system of claim 2 wherein said deflecting means has an apparent center of deflection and said grid is generally spherical and concentric with said center.

4. The display system of claim 1 wherein the beam modifying field means has a nonlinearity which is less than an elemental area of the display, throughout the entire screen surface.

5. The display system of claim 1 wherein the color of the light output of said screen is dependent on the energy of the beam striking the screen and said beam modifying field means responds to the potential from said source to establish an accelerating field which is normal to the path of the deflected beam throughout the scan thereof.

6. The display system of claim 1 wherein the color of the light output of said screen is dependent on the frequency of the beam striking the screen and said beam modifying field means responds to the potential from the source to establish an alternating field normal to the path

of the deflected beam throughout the scan thereof to frequency modulate the beam in accordance with said signal.

7. The color display system of claim 1 wherein said screen has a plurality of sets of color dots arranged in a pattern of elemental areas with an apertured mask immediately adjacent the screen, having apertures therein related to the dots of each set so that the direction of travel of the beam through each aperture determines the color of excitation of the screen and said beam modifying field means responds to the potential from said source to effect diffraction of said beam to vary the direction of its travel through each hole.

8. The display system of claim 5 wherein the color of the light output of said screen is dependent on the velocity of the beam striking the screen and said beam modifying field means responds to the potential from said source to effect a linear variation of the velocity of the beam throughout the scanning range.

9. The display system of claim 6 wherein the hue of the light output of said screen varies with the frequency of the beam striking the screen and the saturation of the light output varies with the amplitude of the beam, and in which the source of color signal includes a means for generating a signal having a frequency representing hue and an amplitude representing saturation.

10. The display system of claim 9 wherein a grid is interposed between the deflecting means and the screen and the color representative signal is applied between the grid and the screen, to effect bunching of the electrons of the beam at the frequency of the color representative signal to excite said screen.
